UNITED STATES PATENT OFFICE.

FREDERICK A. SCHULTZ, OF HASBROUCK HEIGHTS, NEW JERSEY.

EAR-DRUM PROTECTOR.

1,355,276.

Specification of Letters Patent. Patented Oct. 12, 1920.

Application filed September 24, 1919. Serial No. 326,034.

To all whom it may concern:

Be it known that I, FREDERICK A. SCHULTZ, a citizen of the United States, and a resident of Hasbrouck Heights, in the 5 county of Bergen and State of New Jersey, have invented certain new and useful Improvements in Ear-Drum Protectors, of which the following is a full, clear, and exact description.

10 Among the principal objects which the present invention has in view are: to protect the human ear from injury and shock incident to loud concussions, drafts of air and admission of water, and to provide an article 15 of the character mentioned, which is simple and easy of installation in service and removal therefrom; and to cheapen and simplify the construction of the article.

Drawings.

20 Figure 1 is a side view of an article of the character mentioned showing the construction and arrangement thereof in accordance with the present invention.

25 Fig. 2 is a similar view on an enlarged scale.

Description.

As shown best in Fig. 2 of the drawings, 30 the protector is constructed from an integral piece of resilient material such as rubber, and has a handle 7 provided therefor which at all times is accessible for the removal of the protector when the same is installed in 35 service. At the base of the handle 7 is a flange 8. The flange 8 is somewhat rigid, being intended to firmly hold the protector in position when forced within the outer opening of the auditory channel of the ear. 40 The cup-shaped flange 9 is of a more delicate structure and of greater flexibility. The flange 9 conforms to the walls of the channel so as to produce a vacuum when drawn

therefrom. This serves to prevent the accidental dislodgment of the protector. 45

When the protector is installed in service, as shown in Fig. 1 of the drawing, it will be found that it does not impair the hearing of the wearer, due to the fact that the material is flexible enough to respond to all of 50 the atmospheric sound vibrations. At the same time it would serve to resist any undue concussion. Also it prevents cold drafts of air passing to the interior of the ear, thereby preventing ear disorders. It serves to prevent 55 the admission of water when the wearer is swimming, thus overcoming or avoiding many of the ills produced by the accidental admission of water to the ear.

While the article is described as constructed of rubber, I do not wish it to be understood as being limited to the use of such material. Many other substances may be found desirable. All of such materials I consider as being within the scope of the 60 present invention. 65

Claim.

As an article of manufacture, an ear drum protector comprising a handle portion; a 70 cup-shaped flange for insertion in the auditory channel of the human ear, said flange being outwardly tapered to a thin edge for collapsing to conform with the varying sizes of said auditory channel; and a resisting 75 flange intermediate said cup-shaped flange and the exposed end of said handle for limiting the insertion of said cup-shaped flange within said auditory channel, said handle and said flanges being integrally formed 80 from a resilient material, said elements being made of different thicknesses to offer different resistances.

FREDERICK A. SCHULTZ.
